(57) **CLAIM**

The ornamental design for a T-shirt with screen display, as shown and described.

DESCRIPTION

FIG. 1 is a front, left and top perspective view of a T-shirt with screen display, showing my design. FIG. 2 is a rear, right and bottom perspective view thereof. FIG. 3 is a front elevation view thereof. FIG. 4 is a rear elevation view thereof. FIG. 5 is a left side elevation view thereof. FIG. 6 is a right side elevation view thereof. FIG. 7 is a top plan view thereof. FIG. 8 is a bottom plan view thereof. FIG. 9 is another front, left and top perspective view of the T-shirt with screen display of FIG. 1, wherein the screen display is separated with the T-shirt. FIG. 10 is an enlarged view of detail 10 in FIG. 5; and, FIG. 11 is an enlarged view of detail 11 in FIG. 7. The broken lines depict portions of the T-shirt with screen display that form no part of the claimed design. The dot-dash broken lines in FIGS. 5, 7, 10, and 11 depict the boundaries of the enlargements that form no part of the claimed design.
